UNITED STATES PATENT OFFICE.

FRANKLIN P. SACKETT, OF WASHINGTON, DISTRICT OF COLUMBIA.

HEADLIGHT FOR VEHICLES.

1,140,189.

Specification of Letters Patent. Patented May 18, 1915.

Application filed September 2, 1914. Serial No. 859,796.

To all whom it may concern:

Be it known that I, FRANKLIN P. SACKETT, a citizen of the United States, and resident of Washington, in the District of Columbia, 5 have invented new and useful Improvements in Headlights for Vehicles, of which the following is a specification.

My invention relates to head lights for vehicles, and pertains more particularly to the 10 reflectors of such lamps.

The object of my invention is to produce a head light for automobiles, trolley cars and other vehicles from which the upwardly projecting rays are removed.

15 Another object of my invention is to produce a reflector for the head-lamps of said character in which the sector of the reflector adapted to project the rays from the burner upwardly and toward the side on which another vehicle will approach traveling in the 20 opposite direction is made blank or of non-reflective surface, and a still further object thereof is to produce a more simple, cheap and efficient head light of said character 25 than has heretofore been attained.

To these ends my invention includes the combination and arrangement of component parts to be hereinafter described and more particularly pointed out in the claim.

30 In the accompanying drawings in which like reference characters indicate similar parts, Figure 1 is a front view of my reflector, and Fig. 2 is a horizontal sectional view of a head lamp embodying my invention.

35 Referring to the drawings, 1 indicates the case of a lamp having the glass lens 2 therein, the reflector 3 in the back thereof and the burner 4 between the lens and the reflector. The general construction of the lamp 40 may be of any suitable type, and as same forms no part of my invention will not be more particularly described.

The reflector 3, as shown, is concave and circular in shape, and, except as hereinafter 45 described, is of suitable material and polished finish adapted to project the rays of light from the burner 4 through the lens 2 on the opposite side of the burner.

For the purpose of removing the rays of light that would be projected upwardly 50 through the lens and serve no useful purpose to the driver of the vehicle on which the lamp is carried, and to avoid the offensive and blinding effect that such rays produce on the drivers of vehicles approaching from the opposite direction, I 55 have rendered the lower sector 5 of the reflector 3 blank or non-reflective of light. Said non-reflective sector may be off-set from a vertical line, as shown, to blank the rays 60 projected toward the inside of the road ahead to further avoid the offensive glare on the opposite side of the road.

It will be apparent that the full efficiency of a headlight to illuminate a road bed is 65 in no wise impaired by the removal of the upwardly projected rays, and that safety of travel is assisted by the removal of the blinding glare from the eyes of persons within the range of the projected light; and it will 70 be appreciated that my reflector thus described may be varied in the details of its construction within a wide range without departing from the spirit and scope of the claim.

Having thus described my invention, what I claim as new, and desire to be secured by Letters Patent, is—

75 A reflector for vehicle lamps comprising a concave plate, a portion of the face of 80 which is reflective of light and the balance of which is non-reflective, the reflective portion of which comprises a sector extending from approximately the center of the plate to its outer edge, and the balance of which 85 comprises a non-reflective sector of less than one half the surface on the lower portion of the plate adapted to eliminate the upwardly projecting rays from the projected beam and retain the rays directed on the roadway, substantially as described.

FRANKLIN P. SACKETT.
